[57] **CLAIM**

The ornamental design for a holder for fitting an accessory, especially an ear muff, to a safety helmet, as shown and described.

DESCRIPTION

FIG. 1 is a top perspective view of a holder for fitting an accessory, especially an ear muff, to a safety helmet showing my new design;

FIG. 2 is a right end elevational view, the left end being a mirror image thereof; and

FIG. 3 is a bottom perspective view thereof.

FIG. 1

FIG. 2

FIG. 3
